UNITED STATES PATENT OFFICE

ERNEST C. SMITH, OF CHICAGO, ILLINOIS, ASSIGNOR TO INTERNATIONAL HARVESTER COMPANY, A CORPORATION OF NEW JERSEY

MANURE-SPREADER BODY

Application filed August 25, 1927. Serial No. 215,290.

This invention relates to manure spreaders, and has for an object the provision of a practical and successful machine of that type having such novel construction and arrangement of parts that a distinctly superior machine is obtained without having its driving axle above the bottom of its moving load mass.

Users of machines of this class demand that such a machine shall be rugged and yet be as light in weight as possible; they demand that it shall be compact, yet have maximum capacity; they demand that it shall have the minimum of parts, yet be able to perform its various functions successfully under many varying conditions; they demand that it shall be light of draft, and that it shall be such that it may be loaded with a minimum of labor. The illustrative machine meets those demands.

In the accompanying drawings,—

Figure 1 is a side elevation;

Figure 2 is a vertical section particularly illustrating the relative arrangement of the axle, body sills, apron, and load supporting bottom of the machine;

Figure 3 is a view mainly in plan, showing the rear part of the machine with the arrangement of the axle, bottom extension, bearing boxes, and apron particularly;

Figure 4 is a detail view, showing the relation of the axle, the bearing box, and the side wall of the machine at one side of the machine;

Figure 5 is a detail view illustrating the structure of the bearing box and its relation to a retainer secured to the side wall; and

Figure 6 is a detail view of the retainer.

Referring to the drawings, there is disclosed a manure spreader body having supporting sills 10 embracing the axle 11, as indicated in Figure 2. Compactness of body construction and facility of loading of the illustrative machine is promoted by the particular sill structure shown. This includes the downwardly and rearwardly bent portion 12 and the adjoining upwardly and rearwardly bent portion 13. Between these bent portions of the sills and the main bottom portion 14 of the illustrative machine the axle is

located. The main bottom portion preferably terminates forwardly of the axle, as clearly shown in Figure 2, there being secured to this portion an extension 15 preferably in the form of a steel plate which just clears the top of the axle, as shown. This plate is secured to the main bottom portion 14 so that the top surfaces of these two members are in the same plane.

The load supporting body of the machine is completed by side walls 16 and 17 located above the opposite sills 12. These side walls are rigidly secured to the bent portions 12 and 13 of the sills by supports shown as parallel uprights 18 and 19. As indicated in Figure 4 of the drawings, these uprights are offset outwardly of the side wall 16, so that the weight of the machine will be uniformly distributed over the bearing boxes 20, which preferably contain roller bearings for the axle 11. The uprights are connected by a retainer 21 which engages a bearing box to support the weight of the machine. This retainer snugly fits between two upwardly extending lugs 22 and 23 preferably integral with the bearing box, as indicated in Figure 5 of the drawings. This arrangement prevents side slipping of the axle or the wheels relative to the body of the machine.

The retainer 21 also engages the bearing box 20 in such a manner as to prevent rotation of that box with the axle. To this end the retainer is formed with a notch, as indicated at 24 in Figure 6 of the drawings. This notch receives a projection 24' which forms an obstruction to the groove formed by the lugs 22 and 23. The bearing box 20 is also formed at its lower end with a flat faced lug 25 which engages the horizontal flat portion of the sill 10 to prevent turning of the bearing box and adequately maintain the parts in their proper positions.

As indicated in Figure 3 of the drawings, the extension or plate 15 is interposed between the bearing boxes 20 on opposite sides of the machine. Due to the fact that the plate 15 just clears the axle, the bearing boxes extend into positions above the plate. This arrangement of elements promotes lowness of body construction and, therefore, facility

of loading. In Figure 3, the apron or conveyor 26 is partly cut away so as to show the above described structure. Cut out portions of the plate 15 are also shown, as indicated at 27. This formation is for the purpose of receiving the apron sprockets 28, which so guide the apron that its upper run moves along the top surface of the load supporting bottom of the machine.

5 The manure spreader, as shown in Figure 1 of the drawings, includes a conventional wide spreading device 29 and a front truck construction 30, the latter being associated with a tongue 31 and a steering device 32. These 10 devices form no part of the present invention and they are, therefore, not described in detail in this application.

Although the invention has been described with reference to one particular construction, 20 it is to be understood that the invention is not limited to the details thereof, but that it is of a scope commensurate with the subjoined claims.

What is claimed as new is:

25 1. In a manure spreader, a rear axle, a pair of longitudinal sills having portions bent down so as to pass beneath said rear axle and disposed throughout the major portions of their lengths with their top surfaces above the lower side of said axle, bearing boxes 30 located between the bent portions of each sill, and a tight fixed bottom supported by said sills with its under surface just clearing the top of said axle.

35 2. A manure spreader comprising, in combination, a load carrying body, a fixed load supporting bottom for said body having its top surface lying in a single plane, a rearward extension of said bottom of less thickness than the bottom and having its top surface in 40 the same plane, and a through driving axle rotatable through the lower horizontal confine of said bottom and just clearing the under side of said extension.

45 3. A manure spreader comprising, in combination, body side walls, a through axle extending across the side walls, a main bottom part terminating forwardly of the axle with its top surface lying in a plane just above the 50 axle and having the greater part of its body lying within the horizontal confines of the axle, an extension secured to the main bottom part with its top surface in the same plane and extending over the axle, and axle bearing boxes on the axle at either end of the 55 extension and substantially contiguous thereto, said bearing boxes extending above the plane of the top surface of said main bottom portion and said extension and being secured beneath the body side walls.

60 4. A manure spreader comprising, in combination, body side walls, a through axle extending across the side walls, a main bottom part terminating forwardly of the axle with 65 its top surface lying in a plane just above the

axle and having the greater part of its body lying within the horizontal confines of the axle, an extension secured to the main bottom part with its top surface in the same plane and extending over the axle, axle bearing boxes 70 located on the axle at the ends of the extension and substantially contiguous thereto, and means secured to the side walls for holding the bearing boxes from rotation and for maintaining them in position under the side walls.

75 5. A manure spreader comprising, in combination, body side walls, a through axle extending across the side walls, a main bottom part terminating forwardly of the axle with its top surface lying in a plane just above the axle and having the greater part of its body lying within the horizontal confines of the axle, an extension secured to the main bottom part with its top surface in the same plane and extending over the axle, fixed bearing 80 members surrounding the axle and so arranged that the extension is located between them and lies below their tops, and means fixed to the side walls for engaging the bearing boxes to prevent them from rotating.

85 6. A tight bottom manure spreader comprising, in combination, a rear axle, a pair of sills supported by said axle and being bent downwardly and upwardly so as to embrace 90 said axle, a fixed bottom bridging the bent portions of the sills and just clearing the top of said axle, side walls above the sills, and uprights, connecting the bent portions of the sills with the side walls above them, said uprights being located on both sides of the axle 95 at each side of the machine.

100 7. A tight bottom manure spreader comprising, in combination, a rear axle, a pair of sills supported by said axle and being bent downwardly and upwardly so as to embrace 105 said axle, a fixed bottom bridging the bent portions of the sills and just clearing the top of said axle, and bearing boxes located between the bent portions of each sill.

In testimony whereof I affix my signature.

ERNEST C. SMITH.
